(57) **CLAIM**

The ornamental design for a television receiver with animated graphical user interface, as shown and described.

DESCRIPTION

1. Television receiver with animated graphical user interface

1.1 : Front

1.2 : Front

1.3 : Front

The broken lines indicate unclaimed portion of the article that form no part of the claimed design.

The appearance of the transitional image sequentially transitions between the images shown in Reproductions 1.1 through 1.3. The process or period that one image transitions to another image; forms no part of the claimed design.

1 Claim, 3 Drawing Sheets

1.1

1.2

1.3
